[57] CLAIM

The ornamental design for a pencil balloon, as shown
and described.

DESCRIPTION

FIG. 1 is a top plan view of a pencil balloon showing
my new design;

FIG. 2 is a side elevational view thereof, all other sides
being identical;

FIG. 3 is a bottom plan view thereof; and

FIG. 4 is a side elevational view of a modified embodi-
ment of the design shown in FIG. 1-3.

FIG. 1

FIG. 2

FIG. 4

FIG. 3
